UNITED STATES PATENT OFFICE.

THADDEUS S. GRIMES, OF COLUMBUS, GEORGIA, ASSIGNOR TO LUMMUS COTTON GIN COMPANY, OF COLUMBUS, GEORGIA, A CORPORATION OF GEORGIA.

HULLER-GIN.

1,244,196.

Specification of Letters Patent. Patented Oct. 23, 1917.

Application filed December 2, 1916. Serial No. 134,714.

To all whom it may concern:

Be it known that I, THADDEUS S. GRIMES, of Columbus, in the county of Muscogee and State of Georgia, have invented certain 5 new and useful Improvements in Huller-Gins; and I do hereby declare the following to be a full, clear, and exact description of the invention, such as will enable others skilled in the art to which it appertains to 10 make and use the same.

My present invention relates to convertible plain and huller gins.

The primary object is to provide improved means for feeding material into the 15 gin and conducting the hulls and trash out of the hulling breast when the gin is operated as a huller gin.

A further object is to provide a movable structure which may be bodily shifted to 20 move the ginning ribs from the saws so as to stop the ginning operation, thus avoiding having the breast front pivotally hung to the gin casing at its upper or lower end.

As illustrated in the accompanying drawings, Figure 1 is a perspective view showing 25 portion of a cotton gin embodying my improvements with the front board removed. Fig. 2 shows the front board. Fig. 3 is a vertical transverse sectional view. Fig. 4 is 30 an end view. Fig. 5 is an elevation showing the manner of arranging the spikes on the conveyer rollers and the troughs. Fig. 6 is an end view of Fig. 5. Figs. 7 and 8 show various positions of the parts. Fig. 9 shows the 35 formation of the ginning ribs and their attachment to a supporting rail. Fig. 10 is a detail.

In carrying out my invention I aim to 40 provide a feeding surface of the full length of the gin saws and also effective means for conveying the cotton, carrying hulls and other trash with it, continuously along the face of the saw cylinder and the ribs intermediate the saws, that is to say, from about 45 the central portion of the saw cylinder, which will be understood to comprehend about 70 circular saws mounted upon a rotary shaft and having alternating ribs, I conduct the material toward each end of the 50 cylinder and the conveyer and then transfer it to a subjacent conveyer which conducts the material from its ends toward its center and thence through a suitable outlet. As the seed cotton and hulls are fed onto the

top conveyer throughout the length thereof 55 they pass toward its ends, and in contact with the saws where the seed cotton itself is pulled through the ribs by the saws and the hulls and trash stripped off and left behind, it being understood that this is a 60 gradual process, so that by the time the material reaches the outlet for discharge at the center of the lower roller, the hulls and trash have been separated from the seed cotton, and are ready to be discharged. 65

As indicated in the drawing, 1 is the breast of the gin having a saw cylinder 2 with alternating ginning ribs 3. The conveyers are designated by 4 and 5. As shown they consist of a pair of superposed shafts 70 each having two sets of spirally wound spikes. In Fig. 5 the line A, B, indicates the center of each of the conveyers. The spikes 6 of the conveyer 4 are so disposed as to conduct the material from the center 75 of the conveyer toward its left hand end, while the spikes 7 are arranged to conduct the material toward its right hand end. From the ends of the conveyer 4 the material drops onto conveyer 5 where one set 80 of spikes 8 tends to conduct the material from the right hand end toward the center and the other set of spikes 9 conduct the material from the left hand end to the center. 85

10 designates the removable front board of the hulling breast and it is shown provided with two troughs, either or both of which may be perforated to form screens, the upper one 12 adapted to lie beneath the 90 upper conveyer 4 and having openings 11 at its ends and the lower trough 13 adapted to lie beneath the lower conveyer 5. The trough or screen 13 is shown formed with a recess 14 in its edge at the central portion 95 thereof through which the hulls and other refuse matter may be discharged. It will be noted that I am enabled to feed the material onto conveyer 4 throughout its entire length. This promotes the rapid work 100 of the gin. Ordinarily the saws are not able to separate the seed cotton from the hulls in the hulling breast as rapidly as it can be ginned in the roll box. One conveyer alone would not effect proper hulling. It is the 105 coaction between conveyers 4 and 5 which produces the effective results.

A seed apron 15 hinged at 31 is provided

with a central opening 16 in line with the outlet 14 through which the hulls and other particles may pass to a hull conveyer 17. The seed, however, will have had opportunity to drop out through the trough or screen 13, and in this manner are kept separated from the hulls and will be guided by the board 15 into the seed conveyer 18.

As indicated in Figs. 1 and 4 the conveyers may be operated by suitable band wheels 19 and the conveyers may rotate in the same or opposite directions, their described functions depending only upon the spiral arrangement of their respective pairs of spikes.

As illustrated, the saw shaft 20 carries the ginning saw cylinder 2. In addition to the ginning ribs 3 intermediate the saws is a series of huller ribs 21. 22 is the cylindrical roll box space arranged above the saw cylinder; 23 is the roll box front and 24 is the lower section of the plain front when the machine is being used as a plain gin. See Fig. 3. When the parts 23, 24 constitute the front the seed cotton is fed into the roll box at 25 and is acted upon by the saw cylinder 2 and ginning ribs 3 in known manner, 26 being the seed board. When used as a huller gin front 24 is removed and front 1 attached. See Fig. 7. In this arrangement of the parts the material is fed in at 28 where it passes to the conveyers 4, 5 before reaching the saw cylinder 2, passing through the hulling ribs 21.

It is occasionally desirable to render one gin inoperative without discontinuing the motive power which may be operating a battery of gins. For this purpose I provide improved means for moving the breast of the gin bodily outward so that the saws are withdrawn from the roll box and the ribs are withdrawn from the saws. In gins as heretofore constructed the upper part of the breast is hinged at the top and the bottom end is swung out until the saws disappear from between the ribs, or the breast is hinged at the bottom and moves out at the top. By my invention the top and bottom are moved out at the same time.

Figs. 3 and 4 show the breast in ginning position and Fig. 8 shows it moved forward and out of ginning position.

As appropriate means for effecting this shifting of the roll box and ginning ribs I have illustrated the following parts. The roll box heads are indicated at 47. They comprise plates one of which is mounted at each end of the gin and together forming the end head of the roll box space 22. The heads 47 also carry the hulling and ginning ribs as well as the hulling box and the removable front boards 10 and also the conveyers 4 and 5. I provide for shifting these roll box heads laterally to cause the parts to assume the positions shown in

Fig. 3 when in ginning position or out of ginning position as in Fig. 8. Each of the heads is formed at its lower end with a recess 33 adapted to receive a shaft 34 which carries rollers 35. These rollers are formed with teeth 36 on one side adapted to be received by recesses 37 formed on a bracket 60 in the gin leg 49. On their other sides each of the rollers is formed with recesses 38 to receive teeth 39 on a bracket 54 on the lower end of the head 47. These parts are clearly shown in Fig. 7.

At their tops the roll box heads are connected by links 46 and 61 to a shaft 43 having an operating handle 42 (Fig. 4). Rods 44 connect the handle 42 with bell crank levers 45 on the shaft 34 which carries the rollers 35. The handle 42 is provided with a lug 48 which is adapted, when the handle is swung to shift the heads outward, to engage the rod 44, the latter acting as a stop and links 46, 61 being off center as in Fig. 8.

The roll box front 23 is hinged to the heads as at 55 and the huller front head 27 is hinged as at 57. The removable front 10 is hinged to the huller front head 27 as at 56.

As appropriate means for mounting the ginning ribs 3 I have shown them secured to rails 40, 41, mounted in the heads 47. The huller ribs 21 are shown mounted at their upper and lower ends on rails 29, 30, secured to the huller front heads 27.

The operation of the parts thus far described for moving the ginning ribs out of ginning position is as follows: The handle 42 is swung forward, or in the direction of the dart, Fig. 4, until the lug 48 contacts with the rod 44. This causes the links 61, 46 to assume the positions shown in Fig. 8. A link 46 being attached to each of the heads 47 moves the breast outward to the position indicated. While the handle 42 is moving outward, and until its lug contacts with rod 44, this rod is, through the medium of the bell crank 45, rotating the shaft 34 and in consequence the rollers 35 which, by their toothed engagement, carry the gin breast forward, the rollers 35 supporting the weight of the gin breast. When the parts are moved in the reverse direction, that is, to place ribs 3 into ginning position, their movement is limited by brackets or stops 58 and 59, the former acting as a buffer for the rail 40 and the latter for rail 41, these stops being formed in the frame of the machine.

Another important feature of my invention resides in the roll box front 23. This is provided with a beveled extremity 23^a and it describes a sliding movement over rail 29 as it closes, or, if the gin is being used as a plain gin, then it describes a similar movement over seed board 26 of the front 24. (Fig. 10.) This forms a joint sub-

stantially at right angles to the radius having for its center the fulcrum 55 of the part 23. A lug A on the head 47 forms a stop for the front 23. By this means the front 5 may be closed without encountering interference from the seed that may fall from the roll box because the substantially shearing action of the extremity of the front as it closes will brush from the rail any seed 10 that may have collected there. It has heretofore been customary to provide a substantially square joint between the hinged roll box front and the rib rail. This permits seed to collect upon the rail, and prevents 15 the front from closing, in consequence of which it has been customary in starting the roll to move the entire breast or roll box into or out of ginning position. By my invention the roll can be started by a slight 20 movement of this front in and out of position.

I also provide a novel form of ginning rib so formed that it will be proof against choking. As partially shown in Figs. 3, 7 25 and 8, and in detail in Fig. 9, the rail 41 is formed with a strip 50 at its edge adjacent the saw cylinder, that is at the point of engagement of the ribs. Each of the ribs is provided with a lug or projection 51 which 30 bears against the front face of the rail and the rib is rabbeted to receive the strip 50, the extremity 52 of the rib being suitably secured to the rail. As will be understood the main portions of the ribs are just sufficiently spaced apart to admit the saws. Just 35 over the strip 50 and extending rearwardly therefrom each of the ribs is formed with a recess 53. The meeting edges of adjacent ribs thus form a widened slot at this point. 40 At their point of contact with the strip 50, however, and rearward therefrom the ribs are in close contact. I have found that in ginning it frequently occurs that the lint will gather around the ginning ribs at their 45 extremities and will become tied. The purpose of the described construction is to overcome this tendency. The strip prevents the ends of the cotton pulled through the ribs from being caught in the joint between the 50 ribs. The slot formed by the adjacent cut away portions of the ribs constitutes an opening affording ready release of the cotton partially pulled through by the saws and enables this cotton to get back into the 55 roll. This ginning rib is embraced by a pending application for patent filed June 15, 1917 Serial No. 175,008.

I claim as my invention:

1. In a cotton gin, a saw cylinder and a 60 pair of superposed conveyers, a feed space being provided above and throughout substantially the length of the upper conveyer and the cylinder, the upper conveyer having means for conducting the material from the center of said saw cylinder to the ends

thereof and discharging it onto the lower conveyer, said lower conveyer having means for conducting the material from each end of the saw cylinder back toward its center and there discharging it. 70

2. In a cotton gin, a saw cylinder, an adjacent conveyer, a feed space being provided above and throughout substantially the length of said cylinder and said conveyer, and a second conveyer adapted to receive the material from said former conveyer and having two sets of spirally arranged elements adapted to continuously conduct the material toward its center, and an outlet at the center of said second conveyer. 75

3. In a cotton gin, a saw cylinder, a pair of superposed conveyers, the upper conveyer having means for continuously conducting the material lengthwise of said cylinder and in contact therewith and discharging it onto the lower conveyer at its ends, said lower conveyer having means for conducting the material from each of its ends toward its center and there discharging it, and a trough 80 beneath each of said conveyers. 85

4. In a cotton gin, a saw cylinder, a plurality of ginning ribs, a frame on which said ribs are mounted, and means for bodily and laterally shifting said frame relatively 95 to said saw cylinder to move said ribs into or out of ginning position. 90

5. In a cotton gin, a saw cylinder, a roll box, a plurality of ginning ribs, a frame on which said box and ribs are mounted and 100 means for shifting said frame bodily and laterally into and out of operative relation to said saw cylinder. 105

6. In a cotton gin, a saw cylinder, a roll box, a plurality of ginning ribs, a head at each end of said roll box and supporting the latter and said ribs, rollers on which said heads are mounted, and means for shifting said heads bodily and laterally into and out of ginning position. 110

7. In a cotton gin, a frame, a saw cylinder, a roll box, a plurality of ginning ribs, said box and said ribs being movable with said frame, said frame having a roller support, and means for moving said frame 115 bodily and laterally to place said box and ribs into and out of operative relation to said saws.

8. The combination with a gin casing having a gin saw mounted therein, of a roll box head at each end of said casing formed with a recess in its lower portion, a shaft in said recess, ribs carried by said heads, rollers on said shaft and movable in said recesses and supporting said roll box heads, 120 and means for shifting said heads on said rollers relatively to said gin saw. 125

9. In a cotton gin, a movable breast, rollers on which said breast is mounted, brackets for supporting said rollers and having 130

toothed engagement therewith, and means for shifting said breast toward and away from the gin casing.

10. In a cotton gin, a roll box having a pivoted front and a seed board, said front, in its closing movement, being adapted to pass over said seed board closely adjacent thereto.

11. In a cotton gin, a roll box having a pivoted front and a seed board, said front being adapted to swing in an arc over said seed board in its closing action.

12. In a cotton gin, a roll box, a front

therefor having a pivotal connection to said box and a beveled extremity, and a seed board having an inwardly inclined top surface adapted to lie adjacent the extremity of said front when the latter is closed, the contiguous surfaces formed by said front and board being at substantially right angles to the radius having said pivotal connection for its center.

In testimony whereof, I have signed this specification.

THADDEUS S. GRIMES.
